UNITED STATES PATENT OFFICE

146,956

DESIGN FOR A CORKSCREW

Henry C. Howells, Bethesda, Md., assignor to
United States Industries, Incorporated, Wash-
ington, D. C., a corporation of Delaware

Application March 8, 1946, Serial No. 127,269

Term of patent 14 years

(Cl. D44—29)

To all whom it may concern:

Be it known that I, Henry C. Howells, a citizen of the United States, residing at Bethesda, county of Montgomery, and State of Maryland, have invented a new, original, and ornamental Design for a Corkscrew, of which the following is a specification, reference being had to the accompanying drawings, forming part thereof.

Figure 1 is a view in perspective of a corkscrew showing my new design.

Figure 2 is a side elevational view.

I claim:

The ornamental design for a corkscrew, as shown.

HENRY C. HOWELLS.
